UNITED STATES PATENT OFFICE.

RAPHAL AIZENMAN, OF NEW YORK, N. Y., ASSIGNOR TO ROSA AIZENMAN,
OF NEW YORK, N. Y.

DESIGN FOR A STAND FOR PHOTOGRAPH-ALBUMS.

SPECIFICATION forming part of Design No. 36,028, dated August 26, 1902.

Application filed July 19, 1902. Serial No. 116,304. Term of patent 7 years.

To all whom it may concern:

Be it known that I, RAPHAL AIZENMAN, a citizen of the United States, residing at New York, in the borough of Manhattan and State 5 of New York, have invented a new, original, and ornamental Design for Stands for Photograph-Albums, of which the following is a specification, reference being had to the accompanying drawings, forming part thereof.

10 Figure 1 is a perspective view of a stand embodying my design; and Fig. 2 is a horizontal section thereof on line 2 2, Fig. 1.

As shown in the drawings, my stand consists of a frame A, having curved edges and 15 a central rectangular opening and a body B, arranged behind the opening. The body is provided with a lining and with religious images or symbols, such as a miniature stoop b, arranged centrally on the back wall of the body, and the images or statuettes of saints 20 c on the right and left of the stoop. The frame A is provided with a shelf s on its front below the lower edge of the opening.

Having described my invention, what I claim as new, and desire to secure by Letters 25 Patent, is—

The ornamental design for a stand for a photograph-album as herein shown and described.

In testimony that I claim the foregoing as 30 my invention I have signed my name in presence of two subscribing witnesses.

RAPHAL AIZENMAN.
